(57) **CLAIM**

The ornamental design for an optic mount, as shown and described.

DESCRIPTION

FIG. 1 is an isometric view of an optic mount showing my new design;

FIG. 2 is another isometric view of the optic mount shown in FIG. 1;

FIG. 3 is a rear elevational view of the optic mount shown in FIG. 1;

FIG. 4 is a right side elevational view of the optic mount shown in FIG. 1;

FIG. 5 is a front elevational view of the optic mount shown in FIG. 1;

FIG. 6 is a left side elevational view of the optic mount shown in FIG. 1;

FIG. 7 is a top plan view of the optic mount shown in FIG. 1; and,

FIG. 8 is a bottom plan view of the optic mount shown in FIG. 1.

The broken lines represent portions of the optic mount that form no part of the claimed design.
